To all whom it may concern:

Be it known that I, Abe Gelb, a citizen of the United States of America, residing in New York city, county of New York, and State of New York, have invented a new, original, and ornamental Design for an Embroidered Trimming, of which the following is a specification, reference being had to the accompanying drawing, forming part thereof, wherein the figure on the drawing is a plan view of a piece of embroidered trimming, showing my new design.

I claim:

The ornamental design for an embroidered trimming, substantially as shown.

ABE GELB.
